UNITED STATES PATENT OFFICE.

PHILIP C. PETHICK, OF NEW HAVEN, CONNECTICUT.

CALENDAR.

Application filed February 25, 1922. Serial No. 539,159.

To all whom it may concern:

Be it known that I, PHILIP CHESLEY PETHICK, a citizen of the United States, and resident of New Haven, in the county of New Haven and State of Connecticut, have invented certain new and useful Improvements in Calendars, of which the following is a specification.

The present invention relates to calendars belonging to the class of such articles or devices which are generally known as long term or perpetual calendars.

Several of the objects of the invention, among others, are first to provide an efficient calendar which can be instantly and precisely read; secondly, to provide a calendar which may be readily and precisely set for the period of any one month of any year without calculation on the part of the operator; and another object is to provide a useful article at a comparatively low cost which can readily be applied to either a wall or a stand calendar.

Heretofore, many different forms of so-called perpetual or long term calendars have been proposed in which are employed endless travelling bands or other devices which are adjustable into various relative positions for the purpose of indicating selected calendar periods, but invariably in known previous instances, the calendar can only be correctly set by careful calculation on the part of the operator, and furthermore even when determinably set with such precision as may be obtainable with the means provided, the calendar indications frequently have to be read with additions or omissions in a manner that the reader must be thoroughly familiar therewith so as to obtain a correct reading.

According to the present invention, devices or means are designed and arranged whereby any person may with ease correctly and precisely both set and read the calendar indications without any additions or omissions, and with no calculation whatsoever, the only requirement being the proper adjustment of the calendar, first by selection of the year and month and then determinably moving a travelling band or member until a selected guide number or sign thereon matches a code number or sign which is automatically given by setting of the year and month indicating devices.

The principles embodied in this invention together with one embodiment of means

for carrying the invention into effect, will be hereinafter described with reference to the accompanying drawings wherein,—

Figure 1 is a front elevation of a face-plate or base employed with the improved calendar and such plate is applicable either to a stand or a wall calendar.

Figure 2 shows the endless band or travelling member of the improved calendar, and said member is shown as being severed and stretched out so as to show entirely, all the indicating matter printed on that member.

Figure 3 is a detail view showing one face of a year index card as employed with the improved calendar.

Figure 4 is a detail view showing the operative face of a month index card also as employed with the improved calendar, and

Figure 5 is a sectional view taken on line 5—5 of Figure 1.

Referring now particularly to the drawings the improved calendar is provided with a face plate or body 1 having therein apertures or openings 2, 3, 4, 5 and 6 through 80 which are exposed indexes representing respectively the selected year, month, days, a code number and a guide number. The year indexes and code numbers are printed in determined positions and order on a card 7 through 85 which is reversible therefore both sides can be used and thereby each year card is prepared to take care of a period of eight years. The month index cards 8 have only one operative face and as each card takes 90 care of a period of only four months, three cards are required to make up the required number of cards for one year and it will be understood this set of three cards are all that are required for a perpetual period. These 95 month cards 8 have therein apertures 9 and 10 through which the year and code indexes printed on the year card, are separately exposed. It should be noted, the code exposing apertures 10 are variably arranged 100 and that the apertures 9 are in invariable positions so as to register with aperture 2 in the face plate.

The day and guide indexes are printed on an endless band or movable member 11 which 105 is supported at the back of the plate 1 by any suitable means which will permit the said band to travel by operation of any suitable propelling means, not required to be shown herein because if desired said band or member 110 may be operated directly by hand without such means. A receptacle 12 is secured

at the back of the plate 1 and this receptacle provides a convenient pocket to receive the cards which are in operation and to retain said cards in their operative position, as 5 shown, viz; the month index card placed in front of the year index card, and further said pocket serves to hold the reserve month and year cards at the back of the year card. The travelling band 11 passes 10 through slot 13 and in front of the operative month card and a selected part of the day indexes on the said band are exposed through the aperture 4 in the plate 1, below the other exposed indices.

15 As stated above, the improved calendar may be applied for use either in connection with a wall calendar or a stand calendar, the latter being suitable for a table, desk or the like and in which instance as shown in 20 Figure 5, the plate 1 is preferably composed of thin sheet metal, likewise the pocket 12, and as a support for the calendar and protection for the band 11, the supporting base 14 with the turned-up end 15 is provided.

25 In order that the operation of an improved calendar constructed and arranged according to the present invention may be more readily understood, it should be noted that therein several important factors must 30 be considered, one being the arrangement or location of the aperture 10 on the month index cards 8. These apertures must be confined within the space that is exposed by the aperture 5 in the face 1 of the calendar, 35 and which aperture is shown as being divided into twelve divisions. The apertures 10 associated respectively with the months January, February, March and April, when the month card is properly placed in position, will appear respectively in the first, 40 second, third and fourth divisions of aperture 5 and the apertures 10 associated with the months of May to December will appear before the fifth to the twelfth divisions respectively.

45 In preparing the year index cards, the year indications are printed in positions so that they will be shown through the opening 2 and the respective opening 9 in the 50 month cards. The particular arrangement of the row of code numbers for each year appearing on the year cards, must be determined by calculation when the year cards are prepared in the course of manufacturing the calendar. In the drawings the aforesaid code numbers are given for a period of 55 four years and as stated both sides of the card can be used therefore each card may have thereon code numbers prepared for a period of eight years.

60 The traveling day index band, preferably endless, is another important factor or feature of this invention. On this band there are twenty-eight columns making four rows 65 of numerals, each row starting with the nu-

meral and ending respectively with the numbers 28, 29, 30 and 31, and said columns and rows are slightly inclined perpendicularly and horizontally so that the figures are arranged to produce in effect a helix which 70 will bring the figures substantially square with the opening 4 when the said band is in position for operation and through which opening only the figures of seven columns appear at one exposure in proper relation 75 with the week days printed on the face plate over the aperture 4. It will be noted the exposed figures are brought substantially into horizontal alignment beneath the week day indications. By means of the arrangement of the figures or indicating characters on the band 11 representing days of the month any correct and desired combination of days of the month with days of the week of any month and any year may be obtained 80 and precisely indicated. In determining the arrangement of said numbers representing days, consideration is made of the fact that there being seven named days in each week and months of four lengths having twenty- 85 eight, twenty-nine, thirty or thirty-one days, the first day of each month may come on any one of the seven named days of the week, therefore said figures are arranged 90 so that there are twenty-eight columns 95 divisible into groups whereby seven columns are employed for each group of months which are divided, as will be understood into said four groups according to the number of days therein. It will further be noted 100 the columns are numbered in successive order from 1 to 28 inclusive and by means of such numbers guides are given for the setting of the calendar as will now be described.

105 In Figure 1 a correct setting of the calendar is shown and this setting was obtained by first placing the card 8 in the pocket 12 so that the index for said month appeared before the opening 2. Card 7 was then 110 placed behind card 8 so that the figures 1922 appeared through opening 9 in the card 3 and opening 2 in the face plate 1. Code number 23 was shown through aperture 10 in the card 8 and aperture 5 in the face 115 plate 1. The operator then moved the band 11 along so that guide number 23 on the band appeared before aperture 6 in the face 1. The seven columns enclosed by bracket *d* were then exposed through opening 4 in the plate 1. *c* designates a setting of the calendar for the month of February, year 1924. In this instance location of the year card into the position to expose the index for that year would cause the code number 14 to appear and then the band 11 would be moved along until guide number 14 appeared and then the correct setting of the calendar would be obtained, that is, this being a leap 120 year, there would be twenty-nine days indi- 125 130

cated for said month of February and the first of the month would fall on Friday. Other examples of setting the calendar may be referred to and are designated by the 5 letters *a*, *b* and *e* and which latter settings are respectively for January, 1922, April, 1924, and March, 1923. These examples can easily be followed out to prove that the 10 calendar is always exact if the simple rule of matching the guide number with the code number is always followed after selective setting of the year and month card.

The guide and code numbers above referred to are automatically provided and 15 are employed only to guide the adjustment of the calendar. These guide and code numbers are not intended in any way to be used in reading the calendar and which reading it will be understood is always made in a 20 conventional manner without necessitating familiarity with a given key or any omission or addition whatsoever such as required when reading calendars of other types heretofore proposed.

25 I claim—

1. In a calendar of the class described, a body having apertures and separate year, month and day index members for selectively displaying indices representing respectively years, months and days, also code and guide numbers or characters provided respectively on said year and day index members and which code and guide numbers or characters are automatically obtained and provided to operate as determining factors only in the adjustment of the calendar; said index members being capable of determinable adjustment under guidance of said code and guide numbers or characters whereby the calendar is adjustable to present a precise reading without any omission or addition therefrom or thereto.

2. In a calendar of the class described, a body having apertures and separate year, 45 month and day index members for selectively displaying indices representing respectively years, months and days, also code and guide numbers or characters provided respectively on said year and day index members and which code and guide numbers or characters are automatically obtained and provided to operate as determining factors only in the adjustment of the calendar; said index members being capable of determinable 50 adjustment under guidance of said code and guide numbers or characters whereby the calendar is adjustable to present a precise reading without any omission or addition therefrom or thereto, and said year index member having thereon in determined positions the index numbers indicating years, and the guiding means consisting of said code numbers or characters arranged in a calculable and varying order with respect 60 to each year index.

3. In a calendar of the class described, a body having apertures and separate year, month and day index members for selectively displaying indices representing respectively years, months and days, also code 70 and guide numbers or characters provided respectively on said year and day index members and which code and guide numbers or characters are automatically obtained and provided to operate as determining factors 75 only in the adjustment of the calendar; said index members being capable of determinable adjustment under guidance of said code and guide numbers or characters whereby the calendar is adjustable to present a precise 80 reading without any omission or addition therefrom or thereto, said month index member bearing the month indices and having two apertures for each month index, one aperture being located in an invariable position relatively to the respective index and the other aperture being determinably located, and said apertures displaying respectively a year index and a code number on said year index member.

4. In a calendar of the class described, a body having apertures and separate year, month and day index members for selectively displaying indices representing respectively years, months and days, also code and guide 90 numbers or characters provided respectively on said year and day index members and which code and guide numbers or characters are automatically obtained and provided to operate as determining factors only 95 in the adjustment of the calendar; said index members being capable of determinable adjustment under guidance of said code and guide numbers or characters whereby the calendar is adjustable to present a precise 100 reading without any omission or addition therefrom or thereto, and said day index member having thereon numerals arranged in a determined order whereby selective exposure of said member in part will indicate 105 precisely the days of any selected month and the said guide numerals or characters on the latter member for guiding the selective setting thereof relatively to the other members.

5. In a calendar of the class described, a body having apertures and separate year, month and day index members for selectively displaying indices representing respectively years, months and days, also code and guide 120 numbers or characters provided respectively on said year and day index members and which code and guide numbers or characters are automatically obtained and provided to operate as determining factors only 125 in the adjustment of the calendar; said index members being capable of determinable adjustment under guidance of said code and guide numbers or characters whereby the calendar is adjustable to present a precise 130

reading without any omission or addition therefrom or thereto, and said day index member having thereon day indicating numerals arranged in a determined order in 5 twenty-eight columns and four rows to form in effect substantially a helix and said columns being consecutively numbered and which consecutive numbering provides said 10 guide numbers whereby said movable member can be adjusted into selected positions relatively to the other index members for selectively adjusting the calendar.

6. A calendar as described having separately adjustable index members provided 15 with variable indicating matter thereon, each of said members having guiding means whereby said members may be adjusted into determinable positions relatively to each other so as to selectively set the 20 calendar and one of said index members which is employed for indicating the days having thereon one hundred and eighteen 25 numbers arranged in twenty-eight columns and in four rows forming a helix, whereby each of the twenty-eight different combinations of seven consecutive columns, furnishes one of the twenty-eight different combinations of days of the month numbers, precisely and without modification so as 30 to render the calendar readable in the conventional manner.

7. A calendar as described having separately adjustable index members provided

with variable indicating matter thereon, 35 each of said members having guiding means whereby said members may be adjusted into determinable positions relatively to each other so as to selectively set the calendar and one of said index members which is employed for indicating the month having 40 thereon the month indexes, an aperture for each month index arranged in an invariable position with respect to said indexes and another aperture for each index arranged in a variable position to said indexes. 45

8. A calendar of the class described having a body provided with a face plate, apertures in said plate for separately indicating code, year, month, day and guide indices, said code and year indices being provided 50 on removable cards, said month indices being on separate removable cards, said day and guiding indices being provided on an endless band, a receptacle and support for said cards and band, apertures in said month 55 card through which said code and year indices are exposed and said cards and band being capable of adjustment relatively to each other under guidance of said code and guiding indices so as to selectively set the 60 calendar for a determined period.

Signed at New Haven in the county of New Haven and State of Connecticut this 23rd day of February A. D. 1922.

PHILIP C. PETHICK.
